UNITED STATES PATENT OFFICE.

CHARLES H. SAMPSON AND JAMES L. WHITLEY, OF ROCHESTER, NEW YORK.

BUCKLE.

Application filed March 15, 1924. Serial No. 699,557.

Our present invention relates to buckles and clasps and more particularly to belt buckles of the kind used on personal apparel and it has for its object to provide a buckle 5 having improved means for securing the belt at both ends without the necessity of perforating it which means are conveniently operable and uniformly effective. Further improvements are directed toward arrangements in this connection whereby the free 10 end of the belt can be inserted in the buckle with the greatest facility. To these and other ends the invention resides in certain improvements and combinations of parts all 15 as will be hereinafter more fully described, the novel features being pointed out in the claims at the end of the specification.

In the drawings:

Figure 1 is a top plan view of a buckle 20 and fragments of the end portion of a belt the same being constructed in accordance with and illustrating one embodiment of our invention;

Figure 2 is an enlarged longitudinal section therethrough showing the free end of the belt in clamped position;

Figure 3 is a view similar to Figure 2 with the free end of the belt released and showing the manner in which it is originally 30 inserted and

Figure 4 is an enlarged elevation of the inner side of the buckle alone.

Similar reference numerals throughout the several views indicate the same parts.

In the present embodiment of the invention the buckle proper comprises a curved plate 1 having convexity in two directions. The permanently attached end of the belt is indicated at 2 and the free end at 3. On the 35 top and bottom edges of the buckle plate are flanges 4. At one end of these the buckle plate is spanned in spaced relationship to its inner side by a shaft 5 mounted in the flanges and having one end flattened as shown at 6 in Figure 1 to prevent it from turning. A sleeve 7 turns freely on this shaft and is formed as a knuckle on a curved 40 jaw plate 8 the under side of which is serrated or roughened as indicated at 9 to afford a strong gripping surface. The curvature of the jaw plate is that of a spiral and it is so proportioned with reference to the distance of the shaft 5 from the buckle plate that as it rotates on the shaft its gripping

surface very gradually approaches the surface of the plate swinging in a direction toward the body of the belt, that is, toward the tip of the buckle.

The belt is slipped into the buckle between the buckle plate and the shaft 5 and beneath the jaw plate 8. The latter is then pressed down against it and due to the curvature and the swinging mount of the jaw plate it grips the belt end and jams it against the buckle plate. The harder the belt is 60 pulled upon the stronger is this jamming action.

In order to insure the engagement of the jaw plate with the belt with sufficient frictional contact to cause the belt to rotate the 70 jaw plate into jamming position, we provide spring means for actuating the jaw plate in such direction. In the present embodiment an intermediate portion of the knuckle 7 is cut away at 10 and a spring 75 11 is coiled about the shaft 5. One end of the spring bears against the jaw plate 8 at 12 while the other end extends through and is locked to the shaft at 13. The spring does not need to be so strong but what the jaw 80 8 can be turned back easily with the fingers. In fact a groove 14 on the knuckle 7 roughens the latter sufficiently to give a purchase for the fingers that will turn the jaw from the knuckle.

The other end 2 of the belt is held by a clamping member 15 having trunnions 16 turning in the flanges 4. Its edge is serrated at 17 and it is of such a length that when it is turned at right angles to the buckle 90 plate 1 it bites into the material of the belt end 2 and clamps it firmly against the plate. At this time, a lever portion 18 by means of which it is manipulated is inclined toward the center of the plate in the position shown. In order to insure the free 95 passage of the end 3 of the belt beneath the jaw plate 8 and to the inner side of the clamp 15, we provide a thin curved guide plate 19 having an offset 20 at its rear end in 100 which the lever 18 may seat itself so that it forms substantially a continuation of the guide plate and a smooth and unbroken surface is presented along which the belt end may slide.

The front end of this plate 19 is brought to a knife edge at 21 where it contacts with the buckle plate and it is secured in place

to tightly hug the plate by perforated ears 22 that lie against the flanges 4 and are secured by the shaft 5.

We claim as our invention:

- 5 1. In a buckle, the combination with a buckle plate, of a shaft spanning the same, a curved, swinging jaw plate having a knuckle portion on the shaft and adapted to jam a belt against the buckle plate, said 10 knuckle portion being cut away to expose a portion of the shaft, and a spring surrounding the shaft within the cutaway portion of the knuckle and acting to move the jaw plate to operative position.
- 15 2. In a buckle, the combination with a buckle plate, of a shaft spanning the same, a curved, swinging jaw plate having a knuckle portion on the shaft and adapted to jam a belt against the buckle plate, a spring 20 on the shaft acting to move the jaw plate to operative position, and a finger grip on the knuckle portion whereby it may be actuated against its spring.
- 25 3. In a buckle, the combination with a buckle plate and a swinging belt gripping member adapted to pinch one end of a belt against the plate, said member

having a relatively angularly disposed operating portion, of a curved swinging jaw plate adapted to jam the other end of the 30 belt against the buckle plate, and a guide plate extending from the surface of the buckle plate in the region of the jaw plate into cooperation with the gripping member to guide said last mentioned belt end past 35 the latter.

4. In a buckle, the combination with a buckle plate and a swinging belt gripping member adapted to pinch one end of a belt against the plate, said member having a 40 relatively angularly disposed operating portion, of a curved swinging jaw plate adapted to jam the other end of the belt against the buckle plate, a shaft therefor spanning the buckle plate, and a guide plate extending 45 from the surface of the buckle plate in the region of the jaw plate into cooperation with the gripping member to guide said last mentioned belt end past the latter, said guide plate being provided with ears by 50 which it is mounted on the shaft.

CHARLES H. SAMPSON.
JAMES L. WHITLEY.
